COMBINED PANEL AND HANDLE FOR A FOOD WARMING CART OR THE LIKE

Delmar D. Rhoads, Fort Wayne, Ind.

Filed Oct. 31, 1960, Ser. No. 62,686

Term of patent 14 years

(Cl. D10—8)

FIGURE 1 is a perspective view of the combined panel and handle for a food warming cart or the like showing my new design;

FIGURE 2 is a front elevational view of the combined panel and handle for a food warming cart or the like illustrated in FIGURE 1;

FIGURE 3 is a cross-sectional view taken on lines 3—3 in FIGURE 2.

I claim:

The ornamental design for a combined panel and handle for a food warming cart or the like, substantially as shown.
